UNITED STATES PATENT OFFICE

104,162

DESIGN FOR A REFRIGERATOR DOOR HANDLE

George J. Hopkins, Kendallville, Ind., assignor
to McCray Refrigerator Company, Kendallville,
Ind., a corporation of Indiana

Application February 18, 1937, Serial No. 67,729

Term of patent 7 years

To all whom it may concern:

Be it known that I, George J. Hopkins, a citizen of the United States, residing at Kendallville, in the county of Noble and State of Indiana, have invented a new, original, and ornamental Design for a Refrigerator Door Handle, of which the following is a specification, reference being had to the accompanying drawing, forming a part thereof, in which:

Figure 1 is a perspective view of a refrigerator door handle showing my new design, the distinguishing, essential and dominant features or

characteristics of the design being the stepped face plate and the stepped handle thereof as shown;

Figure 2 is a sectional view thereof on line 2—2 of Figure 1; and

Figure 3 is a top plan view of the refrigerator door handle.

I claim:

The ornamental design for a refrigerator door handle, as shown and described.

GEORGE J. HOPKINS.
